UNITED STATES PATENT OFFICE

HENRY RESCH, OF BAYONNE, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed July 30, 1926. Serial No. 125,885.

This invention relates to line-spacing means for typewriting machines, and is designed to increase the range of the usual maximum platen-throw of three line-spaces to a maximum throw of seven line-spaces, or more.

The device is particularly useful in typing reports or certain lists, such, for example, as stock-holders' lists, in which the name and address of the stock-holder are typed in the first column. This usually occupies three lines. In two or more other columns to the right of the sheet appear, in a single line, the number of shares held, the amount of dividends and the number of the bank-check mailed to the stock-holder, or other data. When typing these single lines, it is necessary to jump the platen five, six or seven line-spaces.

These multiple line-jumps on any one work-sheet are uniform, so all that is necessary in my device is to set the parts to a gage for the desired throw of the platen and the operation is accurately accomplished by operating the line-space lever.

To turn the cam-plate on the hub of the ratchet, it may be provided with an integral handle extending upwardly through a slot in a cap-plate resting on and secured to the left-end plate of the platen-frame. The handle near its top may carry an offstanding spring-detent blade having a teat or knob which engages one of a series of holes formed on an arcuate line with the axis of the platen as its center, to yieldingly lock said handle in a desired set position, to cause the pawl to pick up the ratchet at any of seven points and rotate the platen correspondingly, when the line-space handle is operated. Said cam-plate handle may also carry a pointer to enable the operator to quickly set the mechanism for a desired line-space throw of the platen by referring to marked scale-lines inscribed on the aforesaid cap-plate.

Other features and advantages will hereinafter appear.

In the accompanying drawings,

Figure 1 is a perspective view, showing my invention as applied to an Underwood type-writing machine.

Figure 2 is a side elevation of the device on a platen-frame, with the side of the cap-plate omitted.

Figure 3 is a vertical sectional elevation taken about on the line 3—3 of Figure 2.

Figure 4 is a view similar to Figure 2, but with the line-space slide in its rearmost position, and the ratchet-control lever and its pawl at the uppermost or extreme seven-line platen-sweep position.

Figure 5 is a detail plan view of the cap-plate with the cam-plate handle and spring-blade detent in section.

Figure 6 is a detail perspective view of a pointer-device employed.

Referring to the drawings, the platen 10 is mounted on an axle 11, journaled in a left-hand end plate 12 and in another end plate at the right of the machine, which is not shown.

For rotating the platen in line-space direction, a handle 13, provided with a finger-piece 14, is pivoted at 15, on the carriage-frame, and is further provided with an arm 16, to force a slide-plate 17 rearwardly.

This slide-plate operates in suitable guides in the end plate 12 and is held forwardly by a pull spring 18 having one end connected to the machine-frame and the other end connected to a pin 19 on the rear end of the slide-plate.

The platen may be rotated in either direction by a finger wheel or piece 20, to arrange the work-sheets at the first typing position, after which the platen may be driven by the handle 13 and slide-plate 17 through a rock plate or lever 21, mounted to pivot on a screw or pin 22.

This rock-plate has an upwardly-directed short arm 23 forked as at 24 to receive the shank of a screw or headed pin 25 carried by a bracket 26, projecting outwardly from the rear end portion of the slide-plate 17 and upwardly through a slot 27, provided in a cap-plate 28 fastened, as by screws, to the end plate 12 of the platen-frame.

The longer arm 29 of the rock plate or lever 21 is substantially diamond shaped and across its wider portion is a slot 30 cut on an arc with the pivot-pin 22 as its center,

and, at its remote end, the rock-plate carries, on a pivot-pin 31, a line-space platen-feed dog or pawl 32, its nose being pulled inwardly by a spiral spring 33 to normally engage the high spot or raised portion 34 of a cam-plate 35 mounted loosely on a tubular hub 36 of a ratchet-wheel 37 which in turn is fixedly mounted on the platen-axle 11 to rotate therewith.

10 The cam-plate is formed with an upwardly-directed handle 36' extending through a slot 37' in the cap-plate 28 and is provided with a finger-piece 38 and an offstanding spring-detent blade 39, having a knob or teat 40, arranged to interlock with one of a series of holes 41, cut through the side portion of the cap-plate on the arc of a circle with its center at the axis of the platen.

The cap-plate 28 is inscribed with scale-lines 42 and indicating numerals 43, to guide the operator in setting the handle 36' to operate the platen through a predetermined line-space sweep or throw, and, as indicated, the maximum line-space throw of the device here shown is seven line-spaces, but, of course, by making slight changes in the mechanism, a still greater throw or sweep of the platen may be achieved at a single operation of the line-space handle 13.

20 A pointer-device 44 is carried back and forth over the cap-plate 28 along the inner edge of the slot 37 with the handle 36' by a pin 45, which passes into a slot 46, provided in a downwardly-directed tongue 47, having 25 a channeled head 48, engaging the cap-plate 28, at the inner edge of the slot 37, and this head is provided with anti-friction rolls 49, which bear on the under side of said plate to prevent binding of the pointer-device in its 30 movements with the handle.

The ratchet 37 is normally held against rotation by the usual spring-backed detent-arm 50, on the pivot-pin 22. The driving movement of the pawl 32 is limited by a stop 45 51 on the platen-frame.

It will be noted that the varying extents of movement of the platen do not vary the throw or driving movements of the line-space lever and its slide, the extent of these movements being uniform.

The operation of the device will be clear from the foregoing. Upon rocking handle 36', so that the indicator or pointer 44 is opposite the numeral corresponding to the number of line-spaces, it is desired to rotate the platen upon actuation of the line-space lever. The handle is locked in position by teat 40 entering the corresponding hole 41, and the position of the handle 36' will determine the 55 magnitude of the angle through which the pawl 32 will slide ineffectively over raised portion 34, and the point at which the pawl will ride off said raised portion and engage the ratchet during the remainder of its movement and thereby move the platen. By ad-

justing the cam-handle 36', therefore, the platen will be rotated from zero to seven line-spaces (or more) upon actuation of the line-space-lever.

Variations may be resorted to within the 70 scope of the invention, and portions of the improvements may be used without others.

Having thus described my invention, I claim:

1. In a typewriting machine, the combination 75 with a rotatable platen and its axle, of a ratchet-wheel having a tubular hub fixedly mounted on said axle, a cam-plate freely mounted on said hub, a rock-lever pivoted eccentrically of said wheel, a dog pivoted thereto, means for causing the dog to engage the edge of the cam-plate, means for locking the cam-plate at a desired position, and means for rocking said lever to permit the dog to engage a tooth of the ratchet to throw or 80 sweep the platen through a predetermined line-space distance.

2. In a typewriting machine, the combination 85 with a platen-frame, a platen revoluble therein and an axle on which the platen is mounted, of a cap-plate resting on and secured to said frame, said cap-plate being provided with aligned slots, scale-lines and an arcuate line of holes, a ratchet-wheel having 90 a tubular hub keyed to said axle, a cam-plate 95 arranged at the side of the ratchet-wheel and mounted to turn on the hub thereof, said cam-plate having a high portion projecting beyond the teeth of said ratchet, a rock-lever, a dog pivoted to the end thereof, a spring to draw said dog into contact with said high portion but out of contact with said ratchet, means extending through one of the slots in said cap-plate for locking the cam-plate relatively to the ratchet-wheel, and means for 100 operating said lever to cause the dog to engage a tooth of the ratchet-wheel and whirl the platen through a predetermined line-space distance.

3. In a typewriting machine, the combination 110 with a revoluble platen having an axle, of a ratchet-wheel having an integral hub connected to said axle, a rocking lever having an arcuate slot spanning said hub and a pawl on the remote end thereof, means turnable on 115 said hub for engaging the pawl to normally hold it out of engagement with the ratchet, means for causing the pawl to engage a tooth of the ratchet when the lever is rocked, and means for operating said lever.

4. The combination with a revoluble platen having an axle, of a ratchet fixed on said axle and having a tubular hub, a cam-plate provided with a handle and having a rotary bearing on said hub, a spring-detent on said handle to lock it against movement, a rock-lever having a slot to span said ratchet-hub, a pawl on said lever, means for causing the pawl to normally engage the cam-plate out of contact with the ratchet, and means for caus- 125 130

ing the pawl to engage and turn the ratchet to rotate the platen.

5. In a typewriting machine, the combination with a revoluble platen, of line-space mechanism for rotating said platen including a ratchet fixed on the platen-axle and having a tubular hub, a cam-plate turnable on said hub, a rock-lever having a slot through which the hub passes, said lever having a short upwardly-directed forked arm and a forwardly-directed longer arm, a pawl on the last-named arm, means for holding the pawl in contact with the cam-plate out of contact with the ratchet, means for locking the cam-plate against movement, and means for operating the rock-lever to cause the pawl to engage the ratchet and rotate the platen.

6. In a typewriting machine, the combination with a revoluble platen having an axle, of a ratchet, a cam-plate and a rock-lever arranged in face to face contact and relatively movable, said ratchet having a hub fixed to the platen-axle and projecting through said cam-plate and rock-lever and acting as a bearing for the former, said cam-plate being provided with a high peripheral portion extending radially beyond the ratchet-teeth, and with an upwardly-extending handle, a cap-plate having slots in its top portion through which the handle and an arm of the rock-lever project and an arcuate line of holes in its side portion, a detent on the handle to engage one of said holes to lock it in a desired position, a pawl on the rock-lever normally resting on the high portion of the cam-plate, and means for operating said lever for causing the pawl to engage the ratchet and turn the platen.

7. In a typewriting machine, in combination with a line-space lever and its slide and a revoluble platen and its axle, a ratchet fast on said axle, said ratchet having a tubular hub, a cam-plate turnable on said hub, said cam-plate having a high spot extending beyond the ratchet-teeth and a handle formed therewith, a spring-detent blade secured in offstanding relation to said handle, said blade having a teat, a cap-plate having slots and an arcuate row of holes with one of which the teat is adapted to interlock to maintain the cam-plate in a set position, a pointer-device movable with said handle and operating in a slot of the cam-plate, a bracket on the line-space slide, a rock-lever pivoted intermediate its ends and having an arm thereof connected to said bracket, a pawl pivoted to the other arm, and means for causing the pawl to engage the high spot on the cam-plate and to engage a tooth of the ratchet when the line-space lever is operated to turn the platen.

8. In a typewriting machine, the combination with a revoluble platen having an axle, a ratchet-wheel fixed to the axle, and a line-space-lever for operating said wheel, of a pawl for engaging said ratchet-wheel, and

motion-multiplying means between said lever and said pawl to produce abnormally increased rotation of said platen, said means including a lever eccentrically pivoted on the platen-frame, the shorter arm being connected to said line-space-lever and the longer arm to said pawl, said last-mentioned arm having a slot-connection with said axle, whereby it is guided by the latter during oscillation.
